HARRY M. POPE, OF HARTFORD, CONNECTICUT, ASSIGNOR, BY MESNE ASSIGNMENTS, TO MAXWELL MOTOR COMPANY, INC., OF DETROIT, MICHIGAN, A CORPORATION OF DELAWARE.

ELECTRIC SPARKING IGNITER.

1,181,247.

Specification of Letters Patent.

Patented May 2, 1916.

Application filed May 10, 1899. Serial No. 716,197.

To all whom it may concern:

Be it known that I, HARRY M. POPE, a citizen of the United States, residing in the city of Hartford, county of Hartford, State 5 of Connecticut, have invented certain new and useful Improvements in Electric Sparking Igniters, of which the following is a specification, reference being had to the accompanying drawings, forming a part 10 hereof.

This invention relates to devices employed for the production of electric sparks for the purpose of ignition and has for its general object to provide a device of this character 15 which shall not be dependent upon the use of an electric battery for the creation of the current, the use of such a battery being undesirable under some conditions, as when, for example, the igniter is applied to a motor 20 vehicle. The improved igniter has been devised with especial reference to its use in producing the igniting sparks for an internal combustion engine, and some features 25 of the invention are directly related to such use, although the invention, in its broadest aspect, is not of necessity restricted to such use.

One particular object is to provide for the 30 production of an igniter current of great intensity at certain periods only, with corresponding economy at other times as a resultant, and to this end the improved igniter embodies a permanent magnet and an armature wound for an alternating current, one 35 of such parts being rotated with respect to the other. In the application of the igniter to an internal combustion engine the rotated part is driven in a definite relation to the 40 rotation of the engine shaft, so that the spark shall be produced at the proper instant with relation to the movement of the engine piston, such timing of the spark being possible without the aid of additional 45 current controlling devices for the reason that the spark producing current is an alternating current and is strong enough to produce the spark only when it is at or near its maximum phase. The apparatus required is therefore exceedingly simple, particularly 50 when the device is applied to a single cylin-

der engine; if it is applied to a two-cylinder engine or other multiple cylinder engine other controlling devices are necessary in order that the spark shall be produced first in one cylinder and then in the next. In 55 neither case is the required apparatus particularly delicate or liable to injury.

A further object of the invention is to provide for the shifting or varying of the period of greatest intensity of the current 60 without affecting the other advantageous features of the igniter, that is to say, to make it possible to delay or to advance the production of the spark with reference to the movement of the engine piston, it being 65 well understood that it is desirable, in internal combustion engines, to be able to vary the instant of ignition of the charge. This result is easily accomplished with this alternating current igniter by making the non- 70 rotating part of the igniter adjustable so as to advance or delay the maximum phase, that is, the spark-producing phase of the current.

The invention will be more particularly 75 described hereinafter with reference to the accompanying drawings in which, for purposes of explanation, certain practical embodiments of the invention are illustrated.

In the drawings.—Figure 1 is a front elevation of a two-cylinder engine to which the invention is applied, the casing of the engine being partly broken out to show parts within. Fig. 2 is a diagrammatic representation of the igniter and its connections as 80 applied to a single cylinder engine, different positions of adjustment of the non-rotating parts being indicated by dotted lines. Fig. 3 represents conventionally the alternate 85 current curve, illustrating the shifting or variation in time of the high-point of the current phase. Fig. 4 is a vertical central section of an igniter unit and its connected parts as adapted for application to a two-cylinder engine. Fig. 5 is a plan view of the 90 parts shown in Fig. 4, with the casing broken off. Figs. 6 and 7 are detail views, in side and plan view, of the contact making and breaking devices shown in Figs. 4 and 5. Fig. 8 is a diagrammatic representation 95 100

of the igniter and its connections as applied to a two-cylinder engine.

Referring first to the arrangement shown in Fig. 2, which illustrates the application of the invention to a single cylinder engine, a permanent magnet is represented at A, within the fields of which is located an armature B wound for an alternate current. As represented in the figure the field magnet 5 of the invention is relatively stationary, although adjustable about the axis of the armature, which is symmetrical with respect to the common axis of the armature and field and the armature is arranged to be rotated by any suitable means, but at a definite or constant speed ratio with the engine shaft so as to produce a constantly varying or approximately sine wave current. From the coils of the armature connection is established 10 through the primary coils of a transformer or inductor C, the secondary coils of said transformer or inductor being connected with the electrodes at D, located within the cylinder or explosion chamber E of the single cylinder explosive engine. By reference to Fig. 3 it will be readily understood that the igniting spark will be produced at the electrodes D only when the alternating current produced in the primary circuit is at 15 or near the high point of its phase, as indicated by the heavy part x' y' of the continuous line 1, which represents the approximately sine wave curve of the current in its normal position, and can pass by the transformer to the secondary circuit and thence to the electrodes in the cylinder of the explosion chamber. It will be evident 20 also that the spark will be produced at regular intervals, depending upon the speed of rotation of the armature, so long as the relative positions of the permanent field magnet and the armature remain unchanged. If, however, the magnet be partially rotated about the axis of the armature, in the 25 reverse direction to the rotation of the armature, as represented for example, by the lower dotted line position in Fig. 2, the high point of the current phase will also be shifted, as represented by the heavy part x^2 y^2 of 30 the dotted line 2 of Fig. 3, and the instant of production of the spark will be correspondingly advanced. On the other hand, if the magnet be shifted in the opposite direction, as represented by the upper dotted line 35 position in Fig. 2, the high point of the current phase will be shifted, as represented by the heavy part x^3 , y^3 of the broken line 3 of Fig. 3, and the instant of production of the spark will be correspondingly delayed. The 40 igniter would operate with no other parts than those already referred to and indeed without any transformer, which is not an essential element, but in practice it is preferable to provide for a further intensification 45 of the current, as by including in the pri-

mary circuit an ordinary condenser, which is sufficiently represented at b, or for a plurality of sparks and therefore greater certainty of ignition by providing an ordinary vibrator, indicated at b', in connection with the transformer or inductor, or to employ both of these devices together if it is desired to further insure the ignition. It will be understood that these devices operate with their own functions, and that the current, after passing the zero point, accumulates until, at or near the high point, it reaches such a tension as to discharge with sufficient intensity to produce an igniting spark. 70

All of the parts employed in the improved igniter as applied to a single cylinder engine are sufficiently represented by the conventional signs employed in Fig. 2, and it is unnecessary to show them more in detail, particularly as like parts are shown in detail, so far as their construction or relation has to do with the present invention, in other figures of the drawings which illustrate the application of the invention to a two cylinder engine, now to be described. 80

In Fig. 1 two cylinders E are shown, the pistons being severally connected in the usual manner, 180° apart, to a common shaft F. The igniter unit is supported on the main casing F', and is inclosed and protected by a casing F². In this instance the magnet A' is rotated in a determined relation to the rotation of the engine shaft and the armature B' is relatively fixed, but adjustable about the axis of the magnet. As 90 represented in Fig. 4 the magnet A' is secured to the spindle A² which is supported on ball bearings within the casing F², and has secured at its lower end a gear a which meshes with a gear f on the shaft F, which 100 in this case is equal to the gear a, so that the rotated part of the igniter is driven in definite or constant speed ratio with the engine shaft, provision being made in the secondary circuit for taking off the current 105 for the respective cylinders of the engine as the current reaches its maximum at opposite points, either plus or minus, it being understood that the connection is made for each electrode circuit during a short period which 110 indicates the maximum or minimum phase, point or time of the current, as represented by the heavy part x' y' of the line 1, in Fig. 3. The armature B', wound for alternating current, is supported by a cap B² which 115 rests upon the casing F² and is rotatable thereon to a limited extent, at the will of the operator, for the purpose of translating the high point of the current in one direction or the other to vary the instant of production of the spark and consequently, if the igniter is applied to an internal combustion engine, the instant of ignition of the charge. 120

As represented in Figs. 4 and 5, a spring b² may be used to turn the armature in one 125

direction and a cord or wire b^3 may be extended from the armature or cap to any point convenient to the operator to permit of the rotation or rotary adjustment of the 5 armature in the opposite direction. Any suitable means, however, may be employed for effecting the rotary adjustment of the armature.

The devices for taking off the current at 10 the proper time to produce the spark in one and then in the other of the engine cylinders may be of any suitable or desired form. As shown in the drawings, two insulating disks A^3 and B^3 are secured respectively to the 15 permanent field magnet A' and the armature B' . The disk A^3 is provided at proper points with contact plates a^3 , and the disk B^3 carries a corresponding number of pairs of separated contact fingers b^3 through 20 which the circuit is closed by the contact of one of the plates a^3 at the proper time, the said contact fingers being connected with the electrodes D , as shown in Fig. 8, and the secondary winding of the transformer or 25 inductor C . The primary winding of said transformer or inductor is connected with the winding of the armature B' , preferably through a condenser b or vibrator b' , or both, as also indicated in Fig. 8. It will be 30 evident that with the contact plate or plates a^3 of the circuit closer or switch, properly placed, the current in the secondary will be directed to one cylinder or the other at the maximum or minimum part of the phase 35 of the alternate current generated, when it is of sufficient intensity to produce the spark, and will be delivered to the electrodes through the described connections or others suited for the purpose. The period or instant 40 of the spark can be varied or adjusted at the will of the operator by the rotary adjustment of the armature, as already described with respect to Fig. 2, although in this case the adjustment is effected not only 45 by translating the high point, but by changing the point where the contact plate a^3 bridges the connection between the contact fingers b^3 , to keep such circuit closings in harmony with the alternate current phases. 50 It is obviously immaterial, so far as this invention is concerned, whether the armature or the permanent field magnet is rotated, and what means be employed to adjust the non-rotating part, whether a device 55 controlled by the operator or a device controlled by an ordinary governor, and, so far as the use of an alternating current generator is concerned, whether the field be a permanent magnet or not. It is also to be 60 understood that the invention is not to be limited to the precise construction and arrangement of parts shown and described herein.

By the term "fixed igniting device" used 65 in the claims, I mean a device in which one

circuit terminal is not moved with reference to the other in order to produce a spark. Such a device, for example, is one in which fixed electrodes are separated by an air gap, or in which a conductor of high resistance 70 to be heated is secured in circuit.

I claim as my invention,—

1. In an electric igniter, the combination of a field magnet and an armature, one of said parts being rotatable with respect to 75 the other and the other of said parts being susceptible of a rotary adjustability, the rotating part being symmetrically arranged about its axis, means to rotate said rotating part at a constant speed ratio with the engine to generate a constantly varying current, a contact plate carried with the rotatable part, separate contact fingers carried by the relatively fixed part and adapted to contact with said plate, and connections 80 from said fingers to the electrodes.

2. The combination with an internal combustion engine and a casing therefor, said casing having an opening therein, of an electric igniter mounted detachably on the 90 engine casing comprising a generator, and intermeshing gears for operating said generator from the engine, one of such gears being mounted on the engine and the other of such gears being mounted on the igniter. 95

3. The combination with an internal combustion engine and a casing therefor, said casing having an opening therein, of an alternating electric current generator, a frame therefor adapted to be detachably secured 100 to the engine casing and having a part projected into the engine casing through the opening therein, and intermeshing gears for operating the said generator from the engine, one of such gears being mounted on 105 the engine and the other of such gears being carried by the generator frame.

4. The combination with an internal combustion engine having a crank shaft with a gear thereon and a casing therefor, said casing having an opening therein, of an electric igniter mounted on the engine casing and comprising an alternating current generator, a shaft projected within the engine 110 casing and having a gear to be driven by the gear on the crank shaft and carrying the rotatable part of the generator, and means carried by the shaft outside of the engine casing for taking off the high point of the current phase. 120

5. The combination with an internal combustion engine having a plurality of cylinders and a crank shaft with a gear thereon, of a casing inclosing said crank shaft and gear and having an opening therein, an 125 electric igniter mounted on the engine casing and comprising an alternating current generator, a shaft projecting within the engine casing and having on its inner end a gear adapted to be driven from the gear on 130

the crank shaft and carrying the rotatable part of the generator, and an electric switch outside of the engine casing with connections for closing the circuit to the cylinders of the engine successively, the movable member of said switch being carried by said shaft.

This specification signed and witnessed this eighth day of May, A. D. 1899.

HARRY M. POPE.
